COMBINED SUPPORT AND REEL FOR STORING ELECTRIC CORDS AND THE LIKE

Joseph T. Wagner, Sr., 262 Tryon St.,
South Glastonbury, Conn. 06073

Filed May 20, 1974, Ser. No. 471,460

Term of patent 14 years

Int. Cl. D8—99

U.S. Cl. D8—220

FIG. 1

FIG. 6

FIG. 2

FIG. 3

FIG. 4 FIG. 5

FIG. 1 is an isometric view of a combined support and reel for storing electric cords and the like showing my new design;

FIG. 2 is a top plan view;

FIG. 3 is a bottom plan view;

FIG. 4 is a front elevational view;

FIG. 5 is a rear elevational view; and

FIG. 6 is an isometric view of a second embodiment of the design shown in FIG. 1.

I claim:

The ornamental design for a combined support and reel for storing electric cords and the like, substantially as shown and described.
